UNITED STATES PATENT OFFICE

2,644,246

CLOTHES DRIER LINT TRAP

John H. Robinson, Louisville, Ky., assignor to
 General Electric Company, a corporation of
 New York

Application December 27, 1951, Serial No. 263,594

2 Claims. (Cl. 34—55)

1

This invention relates to means for removing lint from clothes dryers of the air circulating type, and more particularly to an improved lint trap for use in such dryers.

In most of the currently popular domestic clothes dryers, the clothes are tumbled in a motor driven drum which rotates within an enclosing casing. The air within the casing is heated by a suitable heater and an air circulating system is provided to induce or force air flow in the vicinity of the heater, usually by means of a motor driven fan. The dryer casing is customarily provided with an intake and an outflow passage to complete the air circulating system, and the heated air, after it has been in contact with the clothes, may discharge into the room in which the dryer is located. Consequently, a screen or other trap is commonly employed to prevent discharge of lint with the air and vapors, but these screens, after several operations of the dryer, collect sufficient lint to impede the free flow of air, thereby materially reducing the drying efficiency. Frequently the operator continues to neglect to clean the screen and the abnormal turbulence resulting from faulty air circulation may then cause some of the lint to settle on the heater or its shielding means. Even though a thermostat is provided to disconnect the power source when the temperature reaches a predetermined level, this thermostat may fail and the air temperature in the casing, particularly in the vicinity of the heater, would increase sufficiently to cause ignition of the accumulated lint.

Accordingly, it is an object of this invention to provide means for automatically bypassing the lint trap and simultaneously removing the lint from the screen upon a predetermined accumulation, so that the flow of air through the discharge outlet will not be impeded.

It is another object of this invention to provide a lint trap arrangement including means for de-energizing the heater and motor upon a predetermined accumulation of lint on the collecting screen.

In carrying out my invention in a presently preferred form, I provide a lint trap for the discharge outlet of a clothes dryer in which the primary lint collecting screen is pivotally mounted at opposite sides of the outlet duct. The pivotal support is located below the longitudinal center line of the screen so that a greater screen area is above the pivot than is below it. Access means are provided so that the screen can be manually tilted to its operating position in which it is substantially vertical or inclined slightly toward the rear

5 of the dryer, as predetermined by suitable positioning means. The weight of the screen and position of the pivots relative to the center of the screen are carefully calculated so that the force necessary to overcome its inertia can be accurately predetermined. The air flow to the outlet of the dryer is not sufficient to tilt the screen forward unless either the rate of flow is abnormal or considerable lint has accumulated 10 on the screen. When the latter occurs, the lint screen offers sufficient resistance to the passage of air through the outlet duct that it is tilted forward to a substantially horizontal position, in which position the accumulated lint will be blown off its surface. If desired, this lint can be permitted to blow upon the floor in the room where the dryer is located thereby serving as a warning to the housewife that too much lint was permitted to accumulate, or, instead, a secondary screen 15 can be added to restrain it. In the latter event, it may be desirable to provide an electrical switch in circuit with the heating and driving means so located that upon tilting of the screen from its vertical position to its horizontal position, the 20 switch will be operated to disconnect the heater and motor. If such a switch is used, then, even though the housewife fails to remove the lint after tilting of the first screen, it will not continue to accumulate until the secondary screen is 25 blocked because the dryer will be rendered inoperative, forcing the user to investigate the source of trouble.

For a better understanding of this invention, attention is now directed to the following description and the accompanying drawings and also to the appended claims in which the features of the invention believed to be novel are particularly pointed out. In the drawings, Fig. 1 is a side sectional elevation of a clothes dryer in which my invention is shown; Fig. 2 is an enlarged perspective view of the lint trap of Fig. 1 with the secondary lint strainer shown disassembled from the remainder of the trap; and Fig. 3 is an enlarged perspective view of the primary lint screen and switch arrangement with the lint screen in its horizontal position.

Referring now to Fig. 1 of the drawings, there is shown a clothes dryer of the domestic air circulating type having an outer shell consisting of a front panel 1, a rear panel 2 provided with louvers 3, and a cover member 4. Suitable side panels, not shown, complete the outer shell. The front panel 1 has an opening to permit insertion and removal of clothes and is provided with a door 5 and a suitable gasket to substantially seal

45

50

55

the opening when the door is in its closed position as illustrated. An inner casing located within the outer shell is provided, consisting of insulated front and rear walls 6 and 7, which are usually of an inverted U-shape, and an insulated side wall and cover panel 8 wrapped thereabout to form a generally horse-shoe-shaped chamber. The front wall 6 is provided with an opening in alignment with the opening in the shell panel 1 to provide entry to the interior of the casing. Within the casing is a non-vertical foraminated tumbler drum 9 suitably supported on a rearwardly extending shaft 10 journaled in an aperture provided for that purpose in the rear wall 7. The tumbler is provided with an opening substantially concentric with its horizontal axis so that, when the door 5 is opened, clothes can be readily loaded into or removed from the drum by the operator.

A driving motor 11 is provided for rotating the tumbler drum through a speed reduction system comprising belts and sheaves or the like. Also driven by the motor 11 is a fan 12 for drawing air through the louvers 3 and into a pressure box 13 from which it is thrown upwardly through longitudinal slots, not shown, in the box along the sides of the panel member 8 and over and through the tumbler drum. This air contacts and is heated by an electric heater 14 located near the top of the dryer casing. It will be understood, of course, that the particular dryer construction is not a part of my invention and may be of any suitable design, such as that shown and described in detail in my application made jointly with Paul L. Paulsen, Serial No. 209,280, filed February 3, 1951, for a Clothes Dryer, and assigned to the General Electric Company, assignee of the present application.

To complete the air circulating system just described, an outlet duct 15 is provided for discharging the exhaust air and vapor through the front of the machine in the space usually referred to as the board area. The duct 15 should be of substantial width to provide a minimum of obstruction to the flow of air therethrough and is customarily provided with a lint trap, to prevent the clothes lint from being discharged into the room. In accordance with my invention this lint trap includes a lint screen 16 pivotally mounted to a pair of pins 17 in the side walls of the duct 15 so that, when in its vertical position, the screen 16 substantially covers the entrance to the outlet duct. The pins 17 support the screen at a point below its longitudinal center line so that a greater screen area is above the pivots than is below them, making it unstable in its upright position. Since the front opening of the duct 15 is either open, or screened by a removable member, as explained hereinafter, the screen 16 may be readily tilted to its vertical position by the operator, and means such as a tab 18 bent out of the bottom of the duct may be used to prevent its being moved beyond a predetermined angle from the vertical. For best results, the screen should be substantially vertical or tilted slightly toward the direction of air flow during its operation. Although the openings in the screen 16 are relatively small, the large area of the screen, and the number of the openings provide a sufficiently low resistance path for the flow of air that the inertia of the screen is not overcome by the usual flow of air unless there is a considerable accumulation of lint thereon. The amount of resistance which must be offered to any predetermined flow of air for the screen to tilt may

be predetermined by a careful choice of the weight of the screen and the position of the pins 17 relative to the longitudinal center line of the screen, as well as by control of the frictional force necessary to turn the screen on its pivots. By careful adjustment at the factory, the screen can be installed so that, upon a predetermined accumulation of lint on its inner surface, a sufficient resistance to the flow of air will result that it will tilt to the position shown in Fig. 3. In this position, the general flow of air across the top surface will sweep most of the lint from the screen and deposit it in the outlet duct past the screen. This lint may then be allowed to be blown into the room so that the operator will be cognizant of the need of cleaning the screen, or it may be caught by an auxiliary screen 19 mounted in a supporting member 20 adapted for ready removal and insertion into the discharge opening of the duct 15. The screen 19 can be removed by the operator and therefore can easily be cleaned. Moreover, since substantially all the lint will blow off the screen 16, it is inherently self-cleaning.

Although not necessary for a successful utilization of my invention, it may in some cases be desirable to add an extra safety feature, especially when the secondary screen 19 is employed. If the operator continued to neglect the lint trap after the screen 16 had become covered with lint and had tilted, the lint would then be blown against the screen 19 and, although most of it would collect along the bottom and leave a considerable screen area for air flow, eventually lint from subsequent operations would completely cover the secondary screen. In this case, the circulation of air would be interrupted, the temperature and pressure within the casing would be elevated above the desirable limits, and the lint might ignite. In order to eliminate this possibility, I have provided switching means including a switch 21 provided with a pushbutton actuator 22. The switch is positioned on the bottom of the duct 15 and arranged in such a manner that the rim of the screen 16 will strike the button to open the switch contacts upon tilting to its horizontal position. By connecting the switch 21 in circuit with the heater 14 and motor 11 in any well known manner, not shown, I have provided means for automatically interrupting the energizing circuit. Thus, the operator will be warned by the failure of the machine to operate that an excessive accumulation of lint has taken place within the discharge duct.

While I have shown a particular embodiment of my invention, it will be understood, of course, that I do not wish to be limited thereto since many modifications may be made; and I, therefore, contemplate by the appended claims to cover any such modifications as fall within the true spirit and scope of my invention.

What I claim as new and desire to secure by Letters Patent of the United States is:

1. In a clothes dryer, an electric air heater, an air discharge duct, an electric motor, a blower driven by the motor for effecting flow of air through said duct, a lint screen in said duct, means pivotally mounting the screen on an axis offset from a central axis of the screen and to one side of the plane of the screen whereby the screen is biased by its weight toward a position across the duct, a stop on a wall of the duct with which the screen engages to hold the screen in such position against such biasing force, and an electric control switch for said heater and motor

positioned on a wall of said duct to be engaged by said screen when it turns on its mounting to a position where it extends longitudinally of the duct, said switch serving also as a stop to limit turning movement of the screen, whereby when said screen becomes clogged with lint it will be turned by the air flow to a position in engagement with said switch to operate the switch and permit air to pass over the screen to blow lint accumulation off the screen toward the duct outlet.

2. A clothes dryer as defined by claim 1 wherein there is provided in the duct beyond the pivoted screen as regards the direction of air flow a read-

ily detachable auxiliary screen for catching lint blown from the pivoted screen.

JOHN H. ROBINSON.
